Harry A. Totten
ATTORNEY.

UNITED STATES PATENT OFFICE.

SAMUEL W. BURTCHAELL, OF OAKLAND, CALIFORNIA.

SHOE-SOLE-CEMENTING APPARATUS.

Application filed February 21, 1927. Serial No. 169,699.

This invention relates to the shoe constructing and repairing art, and more particularly to an appliance for use in cementing soles or heels to the bottoms of shoes.

5 The invention has for its principal objects to provide an appliance capable of cooperation with a shoe last and last jack when these two elements are used in their proper relation in a shoe factory repairing establishment or 10 the like. Another object is to provide a structure whereby an elastic means may be held in tightly stretched position over the sole of a shoe as the shoe is mounted on a last. A further object is to provide a structure or 15 appliance for use in connection with a last of conventional type and which may be removed therewith from a jack, and which is also capable of detachment from the last.

In its broadest embodiment, the invention 20 comprises an open frame for relative cooperative movement with a shoe last, and when in operative position with the shoe bottom uppermost to lie beneath the sole portion and the last, and to maintain stretched or under 25 tension an elastic member or members disposed transversely of the shoe sole in contact therewith; means being provided for releasably holding the frame in its operative position, and if desirable, but not essential, means 30 may be provided for detachably connecting the frame with the shoe last.

With the above mentioned and other objects in view, the invention consists in the novel construction and combination of parts hereinafter described, illustrated in the accompanying drawings, and set forth in the claims hereto appended, it being understood that various changes in the form, proportion, size 35 and minor details of construction within the 40 scope of the claims may be resorted to without departing from the spirit or sacrificing any of the advantages of the invention.

To more clearly comprehend the invention, reference is directed to the accompanying 45 drawings, wherein:—

Fig. 1 is a view in side elevation of the preferred embodiment of the invention in operative position, holding a sole to the bottom of a shoe.

50 Fig. 2 is a transverse sectional view on line 2—2 of Fig. 1 illustrating particularly the

elastic means held under tension in contact with the surface of the shoe sole.

Fig. 3 is a view in top plan of the frame and mounting plate, they being detached from the 55 shoe last.

Fig. 4 is a view in side elevation of the structure illustrated in Fig. 3.

Referring more particularly to the drawings, wherein like characters of reference 60 designate corresponding parts, 1 indicates a conventional shoe jack provided with a tapered upper end 2, a base 2', and a swivel connection between the members 1 and 2. Detachably positioned on the tapered upper 65 end 2 of the jack 1 is a conventional shoe last 3 over which there is adapted to be positioned in a conventional manner, a shoe 4 to be repaired, the latter being illustrated in dotted lines Fig. 1.

5 is an open frame the configuration corresponding somewhat to the outline in plan of the sole portion of the last 3, and also curved to correspond somewhat to the curvature of the sole portion of the last 3, as viewed in side 75 elevation, the frame, however, being of a size to readily receive the last 3 as clearly illustrated in Figs. 2 and 3 of the drawings. As illustrated in the preferred embodiment, one end of the frame is preferably fulcrumed at 6 80 to the upstanding portion 7 of the plate 8 disposed horizontally beneath the last 3, and which plate is provided with an aperture 9 through which is adapted to extend the portion 2 of the jack 1 when the plate is mounted 85 thereon. The plate at its forward edge is illustrated as mounting a pivoted latch 10, the recesses 11 of which are adapted for receiving the free end of the frame and preclude the same from moving upwardly relatively to the last 3 until released.

The plate 8 may be permanently or detachably united to the last 3 in any suitable manner, the structure illustrated affording a detachable connection between the plate and 95 last, and the same is constructed in the following manner:—

On each side of the opening 12 in the last 3 for receiving the mounting end 2 of the jack 1, the last is provided with the parallel spaced 100 recesses 13 formed with the off-set flanges 14. The hooked ends 15 of member 16 extending

in parallel spaced relation upwardly from the upper surface of the plate 8 have hooked engagement with flanges 14. It will be observed that the last 3 is provided with offset flanges 14 for engagement by the hooked ends 15 of the member 16 when the plate and last are assembled. It will also be observed that when the plate and last are positioned as illustrated on the upper end of the jack that the 10 end of the jack passing through the aperture 9 on the plate and the opening 12 in the last holds the last and plate in their relative positions, as illustrated in Fig. 1. The last and plate may only be detached and separated 15 from each other at such time as both are removed from the jack.

A tubular elastic member 17 consisting of several sections or one single section is adapted for endwise movement inwardly of the 20 frame 5 from its free end to be disposed transversely of the upper surface of the sole portion and the last 3.

With the plate 8 mounted as in the drawings and the last 3 positioned on the jack 1, as 25 illustrated, and the shoe to be repaired positioned on the last 3 with the adhesively coated sole in position on the shoe bottom, the frame 5 which has previously been swung on its fulcrum backwardly and hangs in a downward 30 or vertical position, is now swung upwardly, the elastic member 17 either in one piece or of sectional construction is positioned endwise over the frame 5 and the frame is swung downwardly with the side rails 18 thereof 35 lying below the upper surface of the foot portion of the last 3. This action stretches the elastic member 17 transversely of the sole 19, which is being applied, and the engagement of the hook 10 at the end of the frame 5 retains the frame in the desired position until 40 such time as the adhesive has dried or set. Immediately after the engagement of the latch 10 with the free end of frame the last with the shoe mounted thereon and the plate 45 10 may be removed as a unit from the jack 1, and placed aside until such time as the attachment of the sole to the shoe bottom has been completed. This leaves the jack free for other uses, and should it be desired, after the 50 sole has set to the shoe bottom and the plate 8 with its frame 5 may be detached from the last 3 and the last used independently thereof for other work in connection with the jack 1.

I claim:

55 1. In combination with a last jack, a shoe last for detachable association therewith, a pivotally mounted open frame also detachably associated with the jack and removable therefrom with the last, said frame adapted 60 for operative movement downwardly over the jack, elastic means acted on by the frame for stretching over the last on the downward movement of the frame, and means for releasably retaining the frame in its operative position.

2. In combination with a shoe last, an open frame operatively movable over the last, elastic means acted on by the frame for stretching over the last on the operative movement of the frame thereover, means for releasably holding the frame in its operative position, and means for detachably associating the frame and last. 70

3. In combination with a last jack, a shoe last, an open frame operatively movable over the last, tubular flexible means mounted on said frame by longitudinal movement thereover with the frame extending through the opening in said means and acted on by the frame for stretching over the last on the operative movement of the frame thereover and means for releasably holding the frame in operative position, said last and frame adapted for removal as a unit from said jack. 75

4. In combination with a last jack, a shoe last, a pivotally mounted open frame operatively movable over the last, elastic means acted on by the frame for stretching over the last on the operative movement of the frame thereover, means for releasably holding the frame in operative position, said last and frame adapted for removal as a unit from said jack, and means for detachably uniting said last and frame in cooperative relation. 80

5. In combination with a shoe last, a plate affording a support therefor and extending beyond the heel and toe portions thereof, an open frame connected at one end to one end of the plate with its free end arranged for downward swinging movement into operative position over the last with the last projecting upwardly through the frame opening, and arranged to support an elastic band extending over the last and a releasable connection between the plate and frame for retaining the frame in operative position, said plate, last and frame comprising a portable unit. 95

6. In combination with a shoe last, a plate detachably associated therewith, a frame pivotally carried by the plate for downward swinging movement into operative position over the last, means carried by the plate for detachably engaging the frame for retaining the same in operative position, and a tubular elastic member for fitting endwise over the frame, said member adapted on the movement of the frame into operative position to be drawn under tension across said last. 110

7. In combination with a shoe last provided with a jack receiving recess, a plate detachably connected with the last and projecting forwardly and rearwardly thereof beneath the same, a frame pivotally mounted at one end to the plate and for swinging movement into operative position downwardly over the last, latch means cooperating with the plate and frame for holding the latter in operative position, and a tubular elastic member fitted over the frame, and adapted on the movement 115

of the frame into operative position to be drawn under tension over the last.

8. In combination with a last jack, a shoe last, a pivotally mounted open frame operatively movable over the last, elastic means actuated on by the frame for stretching over the last on the operative movement of the frame

thereover, and means for releasably holding the frame in operative position, said last and frame adapted for removal as a unit from 10 said jack.

In testimony whereof I have signed my name to this specification.

SAMUEL W. BURTCHAELL.
